B. W. KENDALL

MULTIFREQUENCY CURRENT TRANSMISSION

Filed August 17, 1920

Inventor:
Burton W. Kendall.

by C. C. Sprague Atty.

UNITED STATES PATENT OFFICE.

BURTON W. KENDALL, OF NEW YORK, N. Y., ASSIGNOR TO WESTERN ELECTRIC COMPANY, INCORPORATED, OF NEW YORK, N. Y., A CORPORATION OF NEW YORK.

MULTIFREQUENCY-CURRENT TRANSMISSION.

Application filed August 17, 1920. Serial No. 404,180.

The present invention relates to the transmission of waves through a medium which causes unequal attenuation of the different waves, and it has for an object the compensation or correction for such unequal attenuation.

In transmission systems particularly those employing long line conductors over which waves of different frequencies are transmitted, it is well known that the waves of the higher frequencies are less perfectly transmitted than those of the lower frequencies. A common instance of this is in telephone systems where the transmitted currents comprise a considerable range of frequencies and the suppression of the high voice frequencies, due to the line characteristics, shows itself in the impaired quality of the received voice waves. The wider the range of frequencies transmitted, the greater is the distortion due to the poorer transmission of the high frequencies relative to the low.

In carrier current systems, it is now common to transmit over the same line currents of a range of frequencies many times as broad as the voice range. These frequencies may extend from a few hundred cycles such as the low frequencies of the voice, or even lower than any voice frequency, up to many thousand cycles. The currents of this wide range of frequency may represent many different messages, and it is necessary to select and separately receive these currents of different frequencies in order to carry on signaling. On long transmission lines it is necessary or desirable to amplify all of these currents at one or perhaps several amplifying or receiving stations. It would be possible to separate the currents of the frequencies used for the various messages, and to provide separate amplifying or repeating circuits for each of the several messages. This method would enable the higher frequency currents to be amplified to any desirable degree independently of the lower frequency currents and thus correct in a measure for their greater attenuation. However, for a considerable number of message channels, the cost of the necessary separating filters and of the large number of amplifiers would be excessive and it is highly desirable that one repeater amplify all of the currents for the same reason that

it is desirable to have one line transmit all of the currents.

In my copending application, Serial No. 334,681, filed October 31, 1919, Patent Number 1,544,910, a multiplex repeater is shown which is capable of simultaneously amplifying a number of independent currents of different frequencies. If such a repeater is to be used for large range of frequencies on a line possessing unequal attenuating properties, it is desirable to associate with the repeater some means for equalizing or correcting or compensating for the distortion due to such attenuation. According to the present invention such provision is made in that repeating coils are used having a transmission efficiency which increases in a predetermined manner with increasing frequencies.

In general, it will be desirable to introduce the means of correction for the line attenuation at the repeater since the correcting means introduces a loss which may be made up by the repeater. The presence of this correcting means also makes it possible to keep the proper relation between the volumes of transmission of the various channels which, because of the characteristics of the line, will be equivalent to suppressing part of the lower frequency transmissions with respect to the higher frequency transmissions. However, it will be understood that the invention is not necessarily limited to an arrangement in which the attenuation correcting device is combined with a repeater, but that this device may be applied to the line at any suitable point whether an amplifier is used or not.

In the drawing to which reference will now be made for the purpose of giving a better understanding of the invention, Fig. 1 is a schematic outlay of a terminal station and a mid-line repeater in a system of the type in which the invention is adapted to be used. Figs. 2 and 3 show repeating circuits embodying the invention or with which the invention is adapted to be associated.

In Fig. 1 the main line ML is arranged for the transmission of both low frequency currents such as those of the voice range and high frequency currents employed as carrier waves. The voice frequency currents are kept from passing to the carrier apparatus

at the extreme left of the figure by the interposition of the high pass filter HF which is so designed as to prevent the passage there-through of currents of frequencies lower than the carrier frequencies, but to pass freely currents of all frequencies above the lowest frequency used in the carrier transmissions. The voice currents of the line ML are selectively transmitted through the low-pass filter LF in the line branch L leading to telephone sets or other low frequency signaling apparatus. Due to the attenuating properties of this filter for currents of high frequencies, the carrier frequency currents of the main lines ML are kept from the line L. The filters HF and LF may be of types disclosed in the patent to G. A. Campbell No. 1,227,113 granted May 22, 1917.

20 The carrier frequency branch contains a hybrid coil H and a balancing network N so designed in connection with the hybrid coil as to enable currents from the transmitting loop TL to be impressed on the line without passing into the receiving loop RL. A number of carrier wave transmitting devices may be arranged for connection to the loop TL, two such sets being diagrammatically indicated. Such a transmitting set may comprise a microphone transmitter T, a modulator M of any suitable type for controlling the energy of the wave transmitted from the carrier frequency source G to the line, and a filter F, preferably a broad band filter, between the modulator and the loop TL. The generator G' of another channel, it will be understood, produces a wave of a different carrier frequency.

Carrier currents received over the line from a distant station pass into the receiving loop RL to which a number of receiving sets will ordinarily be connected. Each such current will be selected to the proper receiving channel by a filter, such as filter F, associated therewith, through which the respective currents selectively pass. A detector D operating in well-known manner enables the low frequency component to be heard in the receiver R.

50 The line ML it will be seen from the above description, serves to transmit currents of a number of different frequencies at the same time. All of these currents transmitted in one direction, for instance to the east, are amplified by the single repeater circuit ER, and those transmitted to the west are amplified by the repeater circuit WR. For preventing singing at the repeater, the usual balancing networks N and hybrid coils may be employed.

The description thus far relates to the general system or type of system to which the invention is particularly applicable. The succeeding figures show specific repeating circuits, embodying the invention, which

may be used in either of the repeating branches ER or WR and which will now be described.

Figure 2 represents a two-stage amplifier of the balanced type similar in general to that shown in my copending application above referred to. The thermionic amplifier tubes 1 and 2 are connected in balanced relation, sometimes termed a "push-pull connection," and are arranged to feed into the second stage, composed of amplifiers 3 and 4, similarly related to each other. By virtue of the balanced connection, together with the proper proportioning of the potential sources 5, 6, 7 and 8, the amplifier circuit as a whole is made to operate with a substantially straight line characteristic, i. e. with the same amplifying factor for all of the impressed electromotive forces, and is therefore capable of repeating currents of a wide range of frequencies with a high degree of purity, and also currents of different frequencies and magnitudes since there is substantially no intermodulation of some frequencies by others. Potentiometers 9 and 10 aid in correctly balancing the circuit, and enable the voltage that is impressed on the amplifiers to be adjusted.

According to the present invention the equalizing of the attenuation of the currents of the different frequencies is accomplished by means of transformer coils having different efficiencies at different frequencies. In Fig. 2 either the input transformer 11 or the output transformer 12 or both may be coils having a gradually increasing efficiency with increasing frequency. The exact design of transformer coils to secure this relation between efficiency and frequency varies with the different conditions to be met. However, it is well known to those versed in the art that the efficiency of a transformer depends upon a number of factors, some at least of which depend upon the frequency. From known transformer formulae, it is possible to calculate the efficiency at different frequencies as these factors are arbitrarily changed, and by controlling these factors it is possible to design a transformer to meet the required conditions.

The coils that are preferably used to practice the present invention have a low mutual impedance. It is well known that a transformer can be represented by an equivalent network consisting of a line with a series impedance proportional to the leakage impedance of the primary coil, a second series impedance proportional to the leakage impedance of the secondary coil and a shunt impedance proportional to the mutual impedance between the coils. In the present invention it is preferred to couple the coils closely so that the magnetic leakage is small. The shunt impedance, which in the actual

transformer is the mutual impedance, comprises both a resistive component and an inductive component. The shunting effect due to the mutual impedance decreases with increasing frequency until a certain more or less definite high frequency is reached beyond which increasing the frequency produces less increase and finally a decrease in the transformer efficiency.

10 By properly proportioning the mutual impedance relative to the line impedances it is possible to make the frequency range over which the loss due to the shunting effect decreases with increasing frequency, coincide with that frequency range over which compensation is desired.

15 In the systems illustrated, to which the invention is applicable, the coils should have a relatively low mutual impedance in order 20 to bring the correcting action within the range of the frequencies transmitted. This low mutual impedance may be secured in a number of possible ways, and in general by using a transformer which has small inductance in the primary and secondary windings. This indicates, for any given 25 transformer ratio which the given conditions may require, a relatively small number of turns in both primary and secondary coils. The permeability of the core and the 30 reluctance of the magnetic circuit also influence the mutual impedance as is well known.

35 It may be stated that in the transformers used experimentally in the development of the present invention, those losses such as eddy current and hysteresis losses, which increase in frequency, were reduced to small value by the use of so-called dust cores similar 40 in general to those disclosed in United States patent to Speed No. 1,274,952, granted August 6, 1918.

45 In Fig. 3 the input coil 13 accomplishes part of the compensation, and another part of the correcting is accomplished by means 50 of the output transformer 14. This use of a plurality of transformers of course permits a greater flexibility in the compensating arrangement than would be practicable 55 with a single transformer. An additional transformer 15, shown in Fig. 3, is inserted to diminish the possible effects of the capacity between the transformer windings. In Fig. 3 but one stage of amplification is indicated, and this is all that will be necessary in some instances. However, a greater number of stages may be used as desired.

60 By the use of the present invention, it has been found possible to correct for the line attenuation over a relatively large frequency range. This makes practicable the use 65 of a single repeater for a multiplex or any other line over which a range of frequencies is transmitted. It is to be understood that the means for carrying out the inven-

tion will be varied considerably to suit conditions, and that the invention is not therefore to be construed as limited to the particular arrangements that have been illustrated and described, but only by the scope 70 of the appended claims.

What is claimed is:

1. In combination, a line, means for transmitting thereover currents of a range of frequencies including a plurality of carrier waves for multiplex telephony, the attenuation of which line varies with the frequency of the transmitted currents, and a transformer associated with said line having a continuously differing transmission 75 efficiency throughout said range of frequencies for correcting for the unequal line attenuation of said transmitted currents by transmitting with greater efficiency the currents that are the more highly attenuated 80 by said line.

2. In a multiplex telephone system, a line, the attenuation of which varies with the frequency of the currents transmitted thereover, means for transmitting simultaneously thereover a plurality of speech modulated carrier waves, a repeater in said line for repeating currents of all the frequencies on said line substantially uniformly, and a transformer for transmitting between the line and the repeater, currents of all the frequencies on said line, said transformer having such a gradually differing transmission efficiency throughout the frequency range of said currents as substantially 90 to compensate for the unequal attenuation by said line of the currents of the different frequencies.

3. In a multiplex signaling system, a line, the attenuation of which varies with the frequency of the transmitted currents, means for simultaneously transmitting thereover a plurality of carrier waves of different frequencies occupying a frequency range several times as extensive as that embraced by essential speech frequencies, a single amplifying repeater circuit for substantially uniformly repeating all of the transmitted currents, and a transformer associated with said repeater and line having a gradually increasing transmission efficiency with increasing frequency throughout said range of transmitted currents for compensating for the unequal attenuation 100 of said currents by said line.

4. In a signaling system, a line, means for transmitting thereover audible frequency currents representing a message together with inaudible frequency currents representing a different message, the attenuation of said line varying with the frequency of the transmitted currents and a repeating coil associated with said line having a transmission loss which varies with the frequency of the currents throughout the total 110 115 120 125 130

frequency range of the currents transmitted over said line in a manner substantially complementary to the variation with frequency of said line attenuation whereby the distortion due to variable line attenuation is substantially corrected for.

5. In a multiplex telephone system, a line for transmitting simultaneously currents representing a plurality of carrier telephone 10 messages, reenforcing repeater means for all of said currents and a common means for impressing all of said currents simultaneously on said repeater means and for correcting for the line distortion for all of 15 said currents.

6. In a multiplex signaling system, a line divided into sections, said line as a whole, having increasing attenuation with increasing frequency, means to transmit over said 20 line a plurality of carrier waves of distinct frequencies each controlled by signals, said signal controlled carrier waves occupying a frequency range several times as extensive as the range of essential speech frequencies, 25 and means for compensating for the unequal line attenuation of the different frequencies comprising a transformer connected between adjacent line sections for transmitting all of said signal controlled 30 waves, said transformer having a low mu-

tual impedance and a transmission efficiency increasing with increasing frequency from the lowest to the highest frequencies in the range transmitted over said line in substantially the same manner as the attenuation of said line increases with frequency. 35

7. In a carrier telephone system, a line divided into sections, said line having a gradually changing attenuation with frequency throughout the total frequency 40 range of currents transmitted over it, means to transmit over said line a plurality of speech modulated carrier waves, and a single repeater circuit between adjacent line sections for amplifying all of the transmitted currents, said repeater circuit including a means serving in common for all of said carrier waves for causing the modulated carrier waves of the higher frequencies received over one line section to be 45 passed to the next line section with greater amplification than the modulated carrier waves of lower frequencies, to compensate for the unequal line attenuation of the currents of the different frequencies. 50

55 In witness whereof, I hereunto subscribe my name this 11th day of August A. D., 1920.

BURTON W. KENDALL.
